By *Robert D. Harvey*
Attorney

UNITED STATES PATENT OFFICE.

ALBERT H. PEGLOW, OF CUDAHY, WISCONSIN, ASSIGNOR TO THE FISK RUBBER COMPANY, OF CHICOPEE FALLS, MASSACHUSETTS, A CORPORATION OF MASSACHUSETTS.

SAFETY DEVICE FOR CALENDERS.

Application filed January 9, 1925. Serial No. 1,446.

My invention relates to a safety device for calenders and more particularly to a guard to prevent the hands of the operators from being caught in the bight of the calender 5 rolls.

In the accompanying drawings, which illustrate one embodiment of my invention,

Figure 1 is a front elevation of a conventional calender equipped with my safety device and

Figure 2 is a section on line 2—2 of Figure 1.

Referring to the drawings I show a three-roll calender having side frames 1 and 2 and rolls 3, 4, and 5. According to one conventional operation a bank of rubber 6 is sheeted out on roll 4, cut into strips on said roll, if desired, and taken off onto a liner 7 passed between rolls 4 and 5. The safety device is indicated generally at 10 and comprises a plate 11 riveted or otherwise secured at its ends to members 12, and rollers 13 and 14 journaled respectively in bearings 15 and 16 formed in members 12. At the rear 15 of the plate and secured thereto I provide a curved plate 16' spaced from roll 4 and extending inwardly to a point adjacent the bight of the rolls 4 and 5. The safety device is suspended before the calender rolls in any suitable manner as by arms 17 secured to members 12 at 18 and mounted to swing on rod 19 secured to the side frames 30 of the calender. The device is yieldingly held in position by springs 20 secured to the members 12 and to bolts or lugs 21 set in the side frames 1 and 2. A handle bar 22 is secured at its ends to members 12 for convenience in swinging the device outwardly when feeding the liner to the calender. In the latter operation it is only necessary to insert the liner beneath roll 14 when the rotation of the roll 5 will carry it between and through the calender rolls. Curved plate 16 prevents the hand of an operator 35 coming in contact with more than one roll if for any reason he inserts his hand behind the guard, and it also serves to prevent premature contact of the liner with the rubber on roll 4.

It will be understood that my invention is not limited to the specific calendering operation described, for instance the liner may be fed over roll 13 instead of under

roll 14 or otherwise handled to conform to any desired calender operation. It will also be understood that my device may be as effectively used to guard the bight of calender rolls when no liner is employed as in conventional coating or frictioning operations.

Having described one embodiment of my invention I claim:

1. In a calender a plate suspended before the calender rolls and adapted to bridge the bight of said rolls, and antifriction devices on the longitudinal edges of the plate.

2. In a calender a plate suspended before the calender rolls adapted to bridge the bight of said rolls and means to maintain the plate in close proximity to the calender rolls said last named means being yieldable to permit access to said rolls.

3. In a calender a plate positioned to bridge the bight of the calender rolls and anti-friction devices on the longitudinal edges of the plate.

4. In a calender a plate yieldingly mounted to bridge the bight of the calender rolls and freely rotatable rolls mounted on the longitudinal edges of the plate.

5. In a calender a plate yieldingly mounted to bridge the bight of the calender rolls, and a member extending inwardly from the plate to a point adjacent the bight of the rolls.

6. In a calender a plate positioned to bridge the bight of the calender rolls and a member conforming substantially to the curvature of the rolls secured to the plate and extending to a point adjacent the bight of the rolls.

7. In a calender a plate mounted to bridge the bight of the calender rolls, anti-friction devices on the longitudinal edges of the plate and a member extending inwardly from the plate to a point adjacent the bight of the rolls.

8. In a calender a plate yieldingly mounted to bridge the bight of the calender rolls, freely rotatable rolls mounted on the longitudinal edges of the plate and a member extending inwardly from the plate to a point adjacent the bight of the rolls.

In testimony whereof I have signed my name to the above specification.

ALBERT H. PEGLOW.
